(57) **CLAIM**

The ornamental design for the hand pruner with extendable handle, as shown and described.

DESCRIPTION

FIG. 1 is a front view of the hand pruner of the claimed design. FIG. 2 is a back view of the hand pruner of the claimed design. FIG. 3 is a left side view of the hand pruner of the claimed design.

FIG. 4 is a right side view of the hand pruner of the claimed design.

FIG. 5 is a top view of the hand pruner of the claimed design. FIG. 6 is bottom view of the hand pruner of the claimed design.

FIG. 7 is a front perspective of the hand pruner of the claimed design.

FIG. 8 is a front view of the hand pruner of the claimed design, with handles extended.

FIG. 9 is a back view of the hand pruner of the claimed design with the handles extended.

FIG. 10 is a left side view of the pruner of the claimed design with the handles extended.

FIG. 11 is a right side view of the hand pruner of the claimed design with the handles extended.

FIG. 12 is a bottom view of the hand pruner of the claimed design with the handles extended.

FIG. 13 is a top view of the hand pruner of the claimed design with the handles extended; and,

FIG. 14 is a front perspective of the hand pruner of the claimed design with the handles extended.

The broken line showing of the hand pruner is included for the purpose of showing portions of the pruner and forms no part of the claimed design.
